UNITED STATES PATENT OFFICE

140,288

DESIGN FOR A DOLL MASK OR SIMILAR ARTICLE

Maurice Marossi, New York, N. Y.

Application November 3, 1944, Serial No. 116,117

Term of patent 3½ years

(Cl. D34—4)

To all whom it may concern:

Be it known that Maurice Marossi, citizen of Czechoslovakia, having his first United States citizenship papers, and resident of New York city, in the county of New York and State of New York, has invented a new, original, and ornamental Design for a Doll Mask or Similar Article, of which the following is a specification, reference being had to the accompanying drawing, forming part thereof, and in which

Fig. 1 is a front elevational view of the doll mask, embodying my new design;

Fig. 2 is a side elevational view thereof; and
Fig. 3 is an axial cross-sectional view.

I claim:

The ornamental design for a doll mask or similar article, substantially as shown.

MAURICE MAROSSI.
